ESCAPE-VALVE FOR STEAM-RADIATORS.

1,210,712.

Specification of Letters Patent. Patented Jan. 2, 1917.

Application filed August 9, 1915. Serial No. 44,560.

To all whom it may concern:

Be it known that I, ZACHARIAH T. Scott, a citizen of the United States, residing at Canton, in the county of Fulton and State of Illinois, have invented certain new and useful Improvements in Escape-Valves for Steam-Radiators, of which the following is a specification.

My present invention relates to a new and improved escape valve for steam radiators and more particularly to a combined check and cut-off valve; and the main object of the invention is to provide an improved valve that is automatically actuated and which will effectually control the water within the coils of the radiator and prevent the same from overflowing.

Another object of the invention is to provide an improved valve of the above character which includes improved valve means to control the entrance of steam or water from the radiator and further, means to limit the movement of said valve means.

A still further object is to provide a device of the type in question that is extremely simple in construction and which it is believed may be manufactured at a comparatively low cost.

Various other objects and advantages will become apparent during the continuance of the following description.

The above and other objects which will become apparent are accomplished by such means as are shown in their preferred form in the accompanying drawings, described in the following specification and then more specifically pointed out in the appended claim.

In the accompanying drawings wherein like characters designate like parts throughout the views, Figure 1 is a view of side elevation showing my invention attached to one of the coils of the radiator. Fig. 2 is a view in vertical section illustrating my invention in its preferred embodiment.

In the accompanying drawings A designates a portion of an ordinary steam radiator in connection with which my invention has been illustrated. However it is to be understood that my invention is not limited to any specific form of radiator whatsoever and that the same may be advantageously used in connection with any of the practical forms.

In its preferred embodiment, my inven-

tion consists of a tubular body portion 10, one end thereof being exteriorly screw threaded as at 11 for reception in a suitable screw threaded opening in one of the radiator coils. The bore of the body 10 is slightly enlarged at an intermediate point as shown at 12 while that portion of the bore adjacent its ends is slightly constricted as at 13 and 14. The constricted portion 14 of the interior bore of the body 10 is interiorly screw threaded so as to receive a screw threaded portion 15 carried on the valve stem 16. The valve stem 16 is in turn provided with a pair of winged extensions 17 by which its manipulation is greatly facilitated. It will be seen that by properly manipulating the valve stem 16 the head 18 thereof may be forced into the seat 19 so as to control the passage of steam or water through the bore.

A collar 20 is carried upon the body portion 10, the inner periphery of the collar being screw threaded so as to receive the exteriorly screw threaded end of the casing 21. An opening 22 communicates with the interior of the casing 21 and the enlarged portion 12 of the interior bore of the body 10 and in view of the fact that the casing 21 is also provided with a vent 23, it will be appreciated that the air in the radiator can be forced outwardly therethrough.

Consistent with the foregoing I have devised an improved means for opening and closing the opening 22 and the vent 23 at certain times which is especially desirable in connection with a device of this character. To this end a float 24 is arranged within the casing 21 and is preferably of a diameter slightly smaller than the diameter of the casing. The lower flat face of the float 24 carries a nipple 25 which, when the float is in its normal position, projects into and closes the opening 22. A pin 26 is carried at the upper end of the float 24 and when the float is in the position in Fig. 2, remains out of engagement with the vent 23.

In Fig. 2 I have shown the body 10 provided with a cross rod 27 that projects into the constricted portion 14 of the interior bore and coöperating with the enlargement 15 prevents the complete removal of the valve stem 16.

Now, in the operation of this device when the same is attached to the radiator the parts will assume a position similar to that shown

in Fig. 2. However as soon as the steam enters the steam pipes adjacent to the radiator the air within the radiator will be subjected to a certain amount of pressure and, 5 consequently forced through the interior bore of the body 10, unseating the nipple 25 and passing through the air vent 28. This operation continues until the water within the radiator flows into the body portion 10. 10 When the water is forced upwardly through the opening 22 the float 24 will of course be actuated, moving the pin 26 into the vent 23. This will prevent the further rise and overflow of the water. After the pressure decreases sufficiently, the float 24 will again drop by action of gravity and atmospheric pressure so as to bring the nipple 25 within the opening 22 and thus close communication between the casing 21 and the body 10 15 and at the same time effect disengagement of the pin 26 with the vent 23.

From the foregoing it is believed that the advantages and novel features will be readily understood and, therefore, further detailed description is deemed unnecessary.

In reducing my invention to practice, I find that the form referred to herein as the most practical and preferred embodiment is the most efficient, but realizing that certain 30 conditions will necessarily vary in concurrence with the adoption of my device, I desire to emphasize the fact that various minor changes in the details of construction and in

the proportion of parts may be resorted to when required without sacrificing any of the 35 advantages of my invention as defined in the appended claim.

Having thus fully described my invention, what I claim as new and desire to secure by Letters Patent is:—

In a valve of the character described, a body portion carrying a longitudinal bore, a valve stem adjustably mounted in said bore, a handle to actuate said valve stem, a head at one end of said valve stem, a valve 40 seat at one end of said bore to receive said head, a casing open at its lower end positioned on said body portion, said body provided with an opening communicating with said bore and said casing, one end of said 45 casing being provided with an air vent, a float arranged in said casing; a nipple carried by one end of said float to normally close said opening, a pin carried at the other end of said float to close said air vent at 50 certain times, and a pin arranged transversely in said body portion and co-operating with an enlargement on said valve stem to prevent the entire removal of the latter.

In testimony whereof I affix my signature 55 in presence of two witnesses.

ZACHARIAH T. SCOTT.
